UNITED STATES PATENT OFFICE

152,776

DESIGN FOR AN ADVERTISING
DISPLAY SIGN

Charles L. Dwinell, Kansas City, Mo.

Application January 19, 1948, Serial No. 143,877

Term of patent 14 years

(Cl. D1—12)

To all whom it may concern:

Be it known that I, Charles L. Dwinell, a citizen of the United States, residing at Kansas City, in the county of Jackson and State of Missouri, have invented a new, original, and ornamental Design for an Advertising Display Sign, of which the following is a specification, reference being had to the accompanying drawing, forming a part thereof.

Figure 1 is a front elevational view of the advertising display sign, showing my new design;

Fig. 2 is a top plan view thereof; and

Fig. 3 is an end elevation view thereof.

I claim:

The ornamental design for an advertising display sign, as shown.

CHARLES L. DWINELL.
